INVENTOR

Herman Stelter.

BY

H. C. Everett & Co.
ATTORNEYS

UNITED STATES PATENT OFFICE.

HERMAN STELTER, OF PITTSBURG, PENNSYLVANIA.

RAILROAD-SWITCH.

SPECIFICATION forming part of Letters Patent No. 634,706, dated October 10, 1899.

Application filed April 14, 1899. Serial No. 712,977. (No model.)

To all whom it may concern:

Be it known that I, HERMAN STELTER, a citizen of the United States of America, residing at Pittsburg, in the county of Allegheny and State of Pennsylvania, have invented certain new and useful Improvements in Railroad-Switches, of which the following is a specification, reference being had therein to the accompanying drawings.

This invention relates to certain new and useful improvements in switches, and more particularly to that class known as "automatic switch-turners" secured to the platform of a car.

The invention has for its object to construct a device of the above-referred-to class that will be extremely simple in its construction, of comparatively few parts, and easy to operate.

The invention has for its further object to construct a device of this character that may be advantageously employed on street-railways, but is particularly designed to be used on railroads and tramways.

With the above and other objects in view the invention finally consists in the novel construction, combination, and arrangement of parts to be hereinafter more particularly described, and specifically pointed out in the claims.

In describing the invention in detail reference is had to the accompanying drawings, forming a part of this specification, wherein like numerals of reference indicate corresponding parts throughout the several views thereof, and in which—

Figure 1 is a side elevation of a portion of a car with my improved switch-turner attached thereto, showing the track in sections, as indicated in dotted lines in Fig. 2, and the operating parts in their proper position. Fig. 2 is a top plan view of the rails, showing in dotted lines my attachment secured in position. Fig. 3 is a transverse vertical sectional view on the line xx , Fig. 2. Fig. 4 is an enlarged detail view in perspective of the swivel-lever operating the frogs. Fig. 5 is an enlarged view in perspective showing the end of said swivel-lever. Fig. 6 is an enlarged perspective view of one of the lever-arms. Fig. 7 is an enlarged detail view in perspective of the antifriction-roller arranged in the

bifurcated end of the swivel-lever, as shown in Fig. 5. Fig. 8 is a detail view of the foot-operating mechanism. Fig. 9 is a detail view 55 of the switch-operating mechanism.

Referring to the drawings by reference-numerals, 1 indicates the platform of a car, which is suitably apertured at 2, in which is arranged a foot-lever 3, carrying a cog-rack 4, engaging a cog-wheel 5, the latter being mounted on the common shaft 6.

6^a represents a pulley-cord secured to the pulley 7, passing over the pulley 9, having its other end connected to the link 12. The pulley 7 is secured to the under side of the platform of the car by a hanger 8.

The reference-numeral 9 indicates a pulley supported by a hanger 10 to the under side of the platform. A hanger 11 is attached to 7^a the under side of the platform, to which is pivotally secured a link 12, pivotally connected at 13 to a link 14, which is pivotally secured at its other end, as shown at 15, to a lever-arm 16, said lever-arm having its forward end pivotally connected at 17 to the end of a stay-rod 18, which is rigidly secured to the under side of the platform. The rear end of the lever-arm 16 is formed into a downwardly-projecting tongue 19, the upper end 8^a of which tongue is secured to a spiral spring 20, the upper end of said spring being secured at 21 to the under side of the car.

The reference-numerals 22, 22 represent the rails of the main line, and 23, 23 the rails of 85 the siding. 24, 24 represent the frogs of the switch. A casing 25 is arranged centrally between the frogs 22, 22 and extends in alignment therewith, said casing having formed therein two slots 26, 26^a. A casing 27 is arranged between the frogs 22, 22 and extends transversely to the casing 25. Within said casing and secured to the sides of the rail are arranged bearing-blocks 28, 28, having pivotally secured therein lever-arms 29, 29, said 95 lever-arms having their free end slightly beveled, as shown at 30, and centrally arranged therein a boss 31, the engaging end of said lever-arms 29 being bifurcated, as shown at 32. The said bifurcated end has formed 100 therein apertures 33 for the reception of the pins 34, 34, connecting the operating-rods 35, 35, which extend and operate in a casing 36, 36. The free ends of the rods 35, 35 are screw-

threaded, as shown at 37 37, carrying an adjusting-nut 38. A spiral spring 39 encircles the end of the operating-rods 35 35.

The reference-numeral 40 represents a bracket which is secured by means of a bolt and nuts 41 to the inner web of the rail, said bracket carrying a swivel-lever 42, said lever being centrally apertured at 43 for the reception of a pin 44, engaging the bracket 40, and the said swivel-lever 42 carries enlarged heads 45, said enlarged heads being slotted, as indicated by the reference-numerals 46 46, the said slots extending at a slight angle of approximately twenty-five degrees. The said enlarged heads 45 are formed with bifurcated ends 47, having apertures 48 48 arranged therein for the reception of the shafts 49 49 of the antifriction-rollers 50 50. The operating-rods 35 35 are adapted to operate between the bifurcated ends 47 of the enlarged heads 45, said bifurcated ends being also arranged to abut against the end of the spring 39. A pin 51 is secured to the under side of the bracket and is adapted to engage the slots 46 46 of the heads 45 of the swivel-lever 42.

It will be understood that there are arranged upon the platform of the car a pair of operating-levers, the one adapted to engage in the slot 26 and the other in the slot 26^a.

30 The operation of my improved device is as follows: For the purpose of illustration it will be presumed that the main line and switch are in position, as shown in Fig. 2 of the drawings, and it is desired to close the switch and continue to travel on the main line. In order to throw the switch in the latter position, a slight foot-power is exerted upon the foot-lever 3, forcing the cog-rack 4 downwardly and imparting motion to the cog-wheel 5, thereby rotating the pulley 7, operating the pulley-cord 6^a, and moving the link 12 downwardly, which in turn operates the link 14, which in turn depresses the lever-arm 16, forcing the downwardly-projecting tongue into the slot 26 and engaging the beveled end 30 of the lever-arm 29, operating the rod 35, which reciprocates in the bifurcated end 47 and against the inner face of the pulley 50. The spring 39 acts as a buffer to take up the sudden jar that would be occasioned by a car moving at a high rate of speed. The operation of the rods 35 35 will communicate motion to the swivel-lever 42, thereby operating the switch in the desired position. When it is desired to open the switch, the opposite foot mechanism is operated and is adapted to engage in the slot 26^a, and the operation will be reversed.

It will be noted that various changes may be made in the details of construction without departing from the general spirit of my invention.

Having thus fully described my invention, what I claim as new, and desire to secure by Letters Patent, is—

1. In an apparatus of the character described, in combination with a car, a lever-arm, suitable means to lower and raise said lever-arm, suitable casings arranged between the rails, a swivel-lever having slots formed therein and extending at an angle thereto, operating-rods connecting said swivel-lever, and lever-arms connecting said rods adapted to engage said lever-arm, substantially as set forth.

2. In an apparatus of the character described, the combination of a foot-lever carrying a cog-rack, a cog-wheel adapted to engage said rack, a set of pulleys secured to the under side of the platform of a car, a pulley-cord operating links of a lever-arm, a lever-arm, rods connected to said lever-arm carrying bifurcated ends, an antifriction-roller, secured to said bifurcated ends, an operating-rod slidably attached to said bifurcated ends, a spiral spring surrounding the end of said operating-rod and a lever-arm attached to said operating-rod adapted to engage said lever-arm of the switch-turning mechanism, substantially as described, and for the purpose herein set forth.

3. In an apparatus of the character described, the combination of a foot-lever having a cog-rack, a cog-wheel arranged below the platform of a car adapted to engage said rack, pulleys, a pulley-cord operating over said pulleys, a link secured to the end of said pulley-cord, a lever-arm adapted to be raised and lowered, a spiral spring secured to said lever-arm, suitable casings arranged between the rails, a swivel-lever mounted on said bracket having formed on its end enlarged heads provided with slots, operating-rods engaging the ends of said swivel-lever, and lever-arms pivotally connected to said operating-rods adapted to engage the lever-arm of the switch-turning mechanism, substantially as herein shown and described.

In testimony whereof I affix my signature in the presence of two witnesses.

HERMAN STELTER.
